REMOVABLE DAUBER AND POLISH SUPPLY
FOR SHOE POLISHING BRUSHES

Oscar T. Broneer, New York, N. Y.

Application June 21, 1946, Serial No. 678,290

1 Claim. (Cl. 15—108)

1

My invention relates to brushes and more particularly to shoe brushes.

The object of my invention is to provide a shoe brush combining a container of shoe polish, a dauber and a shoe brush into one unit.

A further object of my invention is to provide an implement adapted to feed the necessary amount of shoe polish to the dauber without creating any chance of soiling the hands of a user of the implement.

Another object of my invention is to provide a shoe brush having a hollow back adapted to removably receive a shoe polish container therein.

Other objects of my invention, not specifically mentioned, may appear in the following specification describing my invention with reference to the drawing illustrating a preferred embodiment of my invention.

It is, however, to be understood that my invention is not to be limited and restricted to the exact construction and combination of parts described in the specification and shown in the drawing, but that such changes and modifications can be made, which fall within the scope of the claim appended hereto.

In the drawing:

Figure 1 is a vertical longitudinal sectional view of the shoe brush according to my invention.

Figure 2 is a sectional view taken on line 2—2 in Figure 1, and

Figure 3 is a sectional view taken on line 3—3 in Figure 1.

Referring now in detail to the drawing the shoe brush forming the subject matter of my invention has a handle 10, on which a hollow back 11 is formed. The handle 10 and the back 11 can be made from any suitable material, such as plastic, aluminum or the like. If the handle and back are made from plastic, this material can be colored to indicate the color of the shoe polish used in connection with the shoe brush.

The hollow back 11 has a substantially rectangular cross section and in the bottom of the hollow back a plurality of tufts of bristles 12 are embedded.

The top of the hollow back is open and has only a short lip 13 extending rearwardly from the front wall of the back, and a somewhat longer lip 14 extending forwardly from the rear wall of the back 11.

A helical spring 15 is arranged in the hollow back 11 underneath the rear lip 14 and abuts the rear wall of the back with one of its ends.

A container 16 has a rectangular cross-section and an elongated rectangular longitudinal sec-

2

tion. The width of this container 16 is such that it fits snugly into the hollow back and the length of the container such, that the rear end thereof is located underneath the rear lip 14, when the container 16 is placed in the hollow back and the spring 15 has pushed the front end of the container into contact with the front wall of the hollow back.

The container 16 is provided with an outwardly threaded neck 17 on its top adjacent its forward end, so that this neck extends upwardly, out of the back 11 of the brush. The container 16 is filled with liquid shoe polish of any desired color and is closed by a screw cap (not shown).

When the container 16 has been placed into the back 11 the cap is removed and discarded. A dauber, indicated in the drawing in general by the index numeral 18, includes a cover for the neck 17 and a dauber brush carried by the cover for rotation relative thereto.

The cover has an internally screw-threaded neck or boss 19 integrally formed on one side of a flat plate or disc 20 which extends marginally beyond the boss to provide an annular flange

25 22. Boss 19 threads upon the externally screw-threaded cylindrical neck 17 to position the plate 20 over the neck opening. Plate 20 has a small number of holes 21 therein through which polish may flow from the container 16.

30 The brush comprises a flat plate or disc-like member 24 in which bristle tufts 23 are secured. Brush disc 24 has a marginal annular bead 25 of U-shaped cross-section providing an annular channel 26 which receives the annular flange 22 of plate 20 to rotatably mount the brush on the cover, and has a small number of holes 27 which register with the holes 21 in plate 20 in one relative position of plate 20 and disc 24.

35 On the top of the circular flange 22 an upwardly extending semi-globular projection 28 is provided and in the bottom of the disk-like member 24 a corresponding indentation 29 is arranged, so that the hole or holes 27 in the brush disk 24 coincide with the hole or holes 21 in the cover 45 plate 20, when the disc 24 is rotated on the cover, so that the projection 28 engages the indentation 29.

Disc 24 is maintained in close surface contact with plate 20 so that, when holes 21 and 27 are 50 out of registry, flow of polish from the container to the bristle tufts of the dauber brush is positively precluded. As plate 20 and disc 24 are thin, flat members and the holes 21 and 27 may be of any desired size, a free flow of polish to the brush is provided when the holes are brought

into registry and any tendency of the polish to clog the holes is overcome by the relative movement of the plate and the disc.

Bead 25 provides a convenient surface which may be gripped between a thumb and finger to rotate the brush without having the fingers come in contact with the bristles which may have an accumulation of polish thereon.

Liquid shoe polish flows then through these holes, wetting the dauber bristles 23. When the bristles are wet enough the flow of polish is stopped by turning the disk-like member 24 and disengaging the projection 28 and indentation 29.

As long as these two elements are in engagement the disk-like member 24 is secured against accidental rotary movement.

When the polish has been applied to the shoes the bristles 12 are used to shine the shoes.

The above description shows clearly, that a shoe brush according to my invention enables a person to apply the shoe polish and shine the shoes with a simple single implement. The use of such a brush eliminates the disagreeable and often smeary opening and closing of an individual can of shoe polish and the storing of this can, a dauber and a shoe brush.

The shoe polish container can either be refilled or an empty container may be discarded and replaced with a fresh, ready filled container.

Having described my invention I claim as new and desire to secure by Letters Patent:

A shoe brush assembly comprising a hollow back having a bottom wall adapted to retain bristles, side walls, a front end wall, and a rear end wall together surrounding an elongated, rectangular space having an open side opposite said bottom wall, a front transverse lip extending from said front wall and overlying the front end of said space, a rear transverse lip extending from said rear wall and overlying the rear end

of said space, said lips being fixed relative to said hollow back, a handle projecting from said rear wall, a rectangular body having a length less than the length of said space but greater than the distance from one of said end walls to the opposite lip and a width substantially the same as the width of said space received in said space with its end portions beneath said lips, a compression spring between said body and one end wall of said back resiliently holding said body against the opposite end wall and beneath the corresponding lip to releasably retain said body in said hollow back, a threaded neck positioned exteriorly of said hollow back and supported on said body, and a dauber brush supported on said threaded neck.

OSCAR T. BRONEER.
